SIMULATED PROJECTOR AND TARGET

Eldon L. Dale, Long Beach, Calif.

Application September 1, 1950, Serial No. 182,853

5 Claims. (Cl. 273—101.2)

1

This invention relates to an improved target game and consists of improvements of my Patent No. 2,510,382, dated June 6, 1950, for Practice Shooting Apparatus, and consists primarily of a simulated gun which can be aimed at a moving target in such a manner as to acquaint the user with the fundamental requirements of shooting.

An object of my invention is to provide a novel target game or practice shooting device in which the operator observes the moving target in a mirror, and is required to lead the moving object with the gun in order to record a hit.

Another object of my invention is to provide a novel improved target game in which the moving target and a revolving drum are geared together and driven from the same source of power, the movable gun being provided with a contact finger which must seek and engage a contact on the revolving drum to record a hit on the moving object.

A feature of my invention is to provide in a target game a revolving drum with contacts arranged in a tortuous path, these contacts being engaged by the user when the target gun is moved, and when these contacts are engaged a hit is recorded on the target.

Other objects, advantages and features of invention may appear from the accompanying drawing, the subjoined detailed description and the appended claims.

In the drawing:

Figure 1 is a perspective view of an improved target game embodying my invention.

Figure 2 is a top plan view of the same, with parts broken away to show interior construction.

Figure 3 is a diagrammatic view of the hit determining electrical circuit.

Figure 4 is a side view as observed from line 4—4 of Figure 3.

Figure 5 is a vertical sectional view of a simulated pistol.

Figure 6 is a wiring diagram of the solenoid vibrator.

Figure 7 is a perspective view of a simulated machine gun and vibrator construction.

Figure 8 is a vertical sectional view of the vibrating mechanism for the simulated gun.

Referring more particularly to the drawing, the numeral 1 indicates a housing or box in which the various apparatus are housed or mounted. A moving object 2, which may be a simulated airplane, or other device, is mounted for rotary movement above the shaft 3, which is journaled in the housing 1. The image of the object 2 is observed in a mirror 4, the mirror being so positioned that the player can observe this image. 55

2

The player stands back of the simulated gun 5, which gun is pivotally mounted on the post 6, which post in turn is journaled in the housing 1.

While I have shown the object 2 as being a miniature airplane, it is obvious that I may also employ a moving picture reel of some target, such as an airplane, and drive this reel through the well known electric motor. The object 2 is mounted on a contact finger 7, which finger is secured to the shaft 3. It will be evident that the object 2 thus moves in a horizontal circular path, this path being observable in the mirror 4.

A contact disk 8, formed of insulating material, surrounds the shaft 3 and is stationary. This disk is provided with a plurality of spaced contacts 9, all of these contacts project through the disk and are connected to a contact ring 10 which is positioned parallel to the disk 8 and on the side opposite the finger 7. The finger 7 engages the top of each of these contacts 9 successively as this finger rotates. All of this will be evident from the drawing.

A drum 11 also formed of insulating material, is mounted on a shaft 12, journaled in the housing 1. The shaft 12 in turn is rotated by the motor 13, through the medium of the belt 14, or the like, and a second belt or chain 15 extends from a pulley 16 on the shaft 12 to a pulley 17 on the shaft 3. Thus, the shafts 3 and 12 are geared together and, consequently, the target 2 and the drum 11 will rotate synchronously and at a definite gear ratio, each to the other. The drum 11 is provided with a plurality of contacts 18 on its outer surface, and these contacts form a tortuous path on the drum, substantially as shown.

As previously stated, a gun 5 is movable on its trunnion 6, and a finger 19 projects from this trunnion and may engage any one of the contacts 18. The gun 5, however, must be adjusted so that the finger 19 seeks out and engages one of the contacts 18, and the gun may be so arranged that it must be pointed to lead the target in order to instruct the user as to the proper use of a gun on a moving target.

The electrical circuit between the disk 8 and the drum 11 is, as follows:

The wire 20 extends from the finger 19 to a battery 21 and thence to the finger 7. The contact ring 10 has a wire lead 22 extending therefrom, thence to a suitable signal 23, and then to a contact brush 24, which is positioned on the inside of the drum 11 and can engage any one of the contacts 18, as they move past this brush.

In order to record a hit, it is necessary that

the finger 19 be positioned on the proper contact 18, as this contact moves past the brush 24, thus completing the circuit through the contacts 9, the contact ring 10, and the leads 20 and 22.

In Figures 5 to 8, inclusive, I have shown means of simulating a recoil of the target gun.

In Figures 5 and 6, the simulated pistol 25 is mounted on a universal joint 26, in the housing 4. The post 27 extends downwardly from the universal joint and is engaged by the link 28 extending from the core 29 of the solenoid 30. The electrical current to the solenoid 30 is controlled by the trigger switch 31, which closes the contact 32, thus energizing the solenoid 30 and causing the core 29 to jerk the pistol 25 to simulate recoil.

In Figures 7 and 8, the simulated machine gun 33 is mounted on a post 34, to which a horizontal rack 35 is secured. A motor 36 drives a mutilated gear 37, which engages the rack 35. A spring 38 moves the rack 35 in one direction when not engaged by the teeth of the mutilated gear 37. Thus, the gear 37 moves the rack 35 in one direction and the spring 38 moves it in the opposite direction. It causes a continuous vibratory motion to be imparted to the machine gun 33, thus simulating recoil.

In operation, when the motor 43 is started, it will drive the shaft 12 with its attached drum 11. The belt 15 will also drive the shaft 3, which causes the target 2 to revolve around the shaft 3. The image of the revolving target is now observed in the mirror 4, and the gun 5 is aimed at this image, and the operator manipulates the gun 5 around the shaft 6, attempting to cause the finger 19 to follow the tortuous path of the contact 18. The finger 7, as it rotates with the shaft 3, engage the contacts 9 and these contacts are successively electrically connected to the contacts 18, through the brush 21. Thus, if the finger 19 engages the correct contact 18 while the finger 7 engages the contacts 9, then, a complete electrical circuit is established and a hit is recorded or indicated in a suitable manner.

Having described my invention, I claim:

1. An improved target game comprising a housing, a first shaft journalled in said housing, a contact finger on the shaft and rotatable therewith, a contact disk adjacent the shaft and engageable by said finger, said finger continuously sweeping the contactor, a simulated gun, means movably mounting said gun, a drum adjacent the gun, contacts on said drum, a contact finger on the gun selectively engageable with the contacts on said drum, power means driving said drum and drive means connecting said drum and said first shaft whereby the drum and shaft are synchronously rotated, the contacts of said disk and drum being connected in an electrical circuit and signal means in said electrical circuit.

2. An improved target game comprising a housing, a first shaft journalled in said housing, a contact finger on the shaft and rotatable therewith, a contact disk adjacent the shaft and engageable by said finger, said finger continuously sweeping the contactor, a simulated gun, means movably mounting said gun, a drum adjacent the gun, contacts on said drum, a contact finger on the gun selectively engageable with the contacts on said drum, power means driving said drum and drive means connecting said drum and said first shaft whereby the drum and shaft are synchronously rotated, the contacts of said disk and drum being connected in an electrical circuit

and signal means in said electrical circuit, the electrical contacts on said drum being arranged in a tortuous path.

3. An improved target game comprising a housing, a shaft journalled in the housing, an object on said shaft and rotatable therewith, a mirror mounted on the housing, the object being observable in said mirror, a simulated gun mounted on the housing and operable by the player, a disk mounted adjacent said shaft, spaced contacts on the disk, a finger rotatable with the shaft and engaging the contacts on the disk, a drum, means rotatably mounting said drum in the housing, drive means extending to said drum to rotate the same, a second drive means extending from said drum to the first named shaft to simultaneously rotate the drum and the shaft, contacts on said drum, a contact finger on the gun, said last named contact finger sweeping the contacts on the drum, said contacts on the disk and on the drum being connected in an electrical circuit, and signal means in said electrical circuit.

4. An improved target game comprising a housing, a shaft journalled in the housing, an object on said shaft and rotatable therewith, a mirror mounted on the housing, the object being observable in said mirror, a simulated gun mounted on the housing and operable by the player, a disk mounted adjacent said shaft, spaced contacts on the disk, a finger rotatable with the shaft and engaging the contacts on the disk, a drum, means rotatably mounting said drum in the housing, drive means extending to said drum to rotate the same, a second drive means extending from said drum to the first named shaft to simultaneously rotate the drum and the shaft, contacts on said drum, a contact finger on the gun, said last named contact finger sweeping the contacts on the drum, said contacts on the disk and on the drum being connected in an electrical circuit, and signal means in said electrical circuit, said contacts on the drum being arranged in a tortuous path.

5. An improved target game comprising a housing, a shaft journalled in the housing, an object mounted on said shaft and rotatable therewith, a mirror on the housing, the image of said object being observable in the mirror, a simulated gun movably mounted on the housing and operable by the player, a second shaft journalled in the housing, a drum mounted on the second shaft, an electric motor, drive means extending from the motor to the second shaft, drive means extending from the second shaft to the first shaft whereby both of said shafts are synchronously rotated, a contact disk mounted adjacent the first named shaft, spaced contacts on said disk, spaced contacts on the periphery of said drum, a contact finger on the first named shaft, sweeping the contacts on said disk, a second contact finger on said gun sweeping the contacts on the drum, the contacts on said disk and on said drum being connected in an electrical circuit, and signal means in said electrical circuit.
